(57) **CLAIM**

The ornamental design for a solar panel frame member, as shown and described.

DESCRIPTION

FIG. 1 is a top, front, right side perspective view of a solar panel frame member, showing our new design;

FIG. 2 is a bottom, front, right side perspective view thereof;

FIG. 3 is a left side elevation view thereof; and

FIG. 4 is right side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The solar panel frame member is shown with a symbolic break, in the form of a wavy line, at the rear side. This symbolic break defines the boundaries of the claim.
